CLAIM

The ornamental design for a windshield repair bridge, as shown and described.

DESCRIPTION

FIG. 1 is a perspective view of a windshield repair bridge showing our new design with an injector shown mounted to the bridge in broken lines for illustrative purposes only and forms no part of the claimed design;

FIG. 2 is a front end elevational view thereof;

FIG. 3 is a rear end elevational view thereof;

FIG. 4 is a top plan view thereof;

FIG. 5 is a bottom plan view thereof; and,

FIG. 6 is a side elevational view thereof, an opposite side being identical thereto.
